(57) **CLAIM**

The ornamental design for a suit jacket lapel, as shown and described.

DESCRIPTION

FIG. 1 is a front prospective view of a suit jacket lapel showing my new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a bottom plan view thereof.

The broken lines showing a suit jacket are for illustrative purpose only and forms no part of the claim.
